PROTECTING HOOD

William R. Shields, Detroit, Mich., assignor to
Hi-Production Wheel Corporation, Detroit,
Mich., a corporation of Michigan

Application July 31, 1937, Serial No. 156,788

3 Claims. (Cl. 51—272)

This invention relates generally to abrading apparatus and refers more particularly to improvement in machine operated abrading apparatus.

5 It is an object of the invention to provide a rotary abrading apparatus in combination with a shield formed of soft resilient material and supported by a stationary part of the apparatus.

It is a further object of the invention to provide 10 a shield for a high speed wet type abrader in which the abrading element is specially formed to cooperate with a specially designed shield so as to prevent radial throwing off of liquid by the centrifugal action of the abrading element.

15 It is a further object of the invention to provide a soft resilient shield in an abrading apparatus which is reinforced to impart rigidity to the shield.

The foregoing, as well as other objects, will be 20 made more apparent as this description proceeds, especially when considered in connection with the accompanying drawing, wherein

Fig. 1 is a side elevation of the device with a portion of the shield broken away;

25 Fig. 2 is a side elevation of the shield element partially in section, and

Fig. 3 is a top view of my improved shield.

The device as a whole includes a rotary abrading element 10 which is secured to and rotatably 30 driven from a stationary element 20. The shield 30 is attached to the stationary element 20.

The rotary body 10 comprising the abrading element is made up of two disk shaped pads, a rear pad 12 and a front pad 11. These pads are 35 provided with forward faces of soft gum rubber and rear faces of relatively hard composition rubber and fabric. The forward working pad 11 is slightly dished on its forward face to provide a concave surface and in this concave surface is 40 positioned a soft double convex filler pad (not shown) made of gum rubber. A sheet of abrading material 13 is stretched over the forward face of the pad 11 and tabs 14 extend around this pad and engage suitable securing means on the 45 rear surface thereof. These securing means are received in a groove (not shown) in the forward face of the rear pad 12. The rear pad 12, the forward pad 11, the filler pad (not shown) and the sheet of abrading material are centrally apertured as at 16 to provide a passage for liquid to 50 be used in the finishing operation, the passage 16 extending axially of the drive shaft 25.

A stationary element 20 is provided and has a gear box 21 in which are provided suitable reduction gearing, if desired, through which the

rotary abrading element 10 is driven. A flexible conduit 26 is connected to the gear box 21 and through this conduit extends a flexible drive shaft (not shown) which connects to suitable power source. The gear box 21 also has a connection 5 22 to which is secured a flexible passage 23 leading to a source of suitable liquid supply such as water. A valve 24 is provided in the connection whereby the abrading device may be used either with water supplied to the working surface 10 thereof or dry.

The abrading device disclosed herein is adapted to be driven at relatively high speeds on the order of 1100 R. P. M. for certain surfaces. The device is capable of numerous applications and may be 15 used to finish surfaces which are unfinished, finished or painted. It may be used for polishing instead of abrading by replacing the sheet of abrading material with a sheet of felt, sheepskin, canvas or the like. It is well adapted for finishing 20 the surfaces of automobile bodies. It has been found that when operating this device at the relatively high speed mentioned, if the rotary body is inadvertently brought in contact with a projection on the surface being finished, such for 25 example as hinge on an automobile body, there is a strong likelihood that the projection will tear the sheet of abrading or finishing material or will damage the relatively soft material of the pads 11 or 12. It has also been found that when 30 the device is being used with water supplied to the working surface through the central conduit 16 that due to the centrifugal action the water is thrown off radially, causing discomfort to the operator and other undesirable results which will 35 be obvious.

I have therefore provided a shield 30 which is secured to the stationary or handle portion 20 of the abrading device and which extends in spaced relation about the rotary abrading element 10. 40 This shield is preferably formed of a soft material such for example as rubber. The forward edge of the shield element 30 terminates a short distance rearwardly of the forward face of the rotary abrading element 10. The rotary abrading element 10 as described above is relatively 45 soft on its forward working face, so that it may conform to irregularities in curvature in the surface being finished. The forward edge of the shield element 30 is spaced rearwardly from the 50 forward working face sufficiently so that it will not interfere with desirable deformation of the forward working surface.

It should be particularly noted that the forward face of the abrading element 10 is provided 55

with outer curved edges 17. The relationship between the curved edges 17 and the forward edge of the shield element 30 is such that the curvature of the edges 17 extends well within the confines of the shield element 30 for a purpose which will later appear.

The shield element 30 has a cylindrical collar portion 31 adapted to fit the cylindrical portion of the gear box 21 in tight gripping relationship. 10 This collar forms the sole support for the shield, the balance of the shield being spaced from the rotary abrading element 10. From the forward edge of the collar 31 the shield extends outwardly, presenting a flat annular portion 31a and from the outer edge of the flat annular portion 31a, the shield extends forwardly presenting a cylindrical portion 32. A bead 33 is formed peripherally about the forward edge of the shield, and suitable reinforcing means such as a wire 34 is imbedded in the bead to impart stiffness thereto. 15 If desired, in order to increase the rigidity of the shield as a whole, suitable ribs 35 may be provided extending radially outward on the flat annular portion 31a and axially forward on the cylindrical portion 32 to the bead 33.

In operation, the soft resilient shield 30 serves three functions. In the first place, it prevents the rotary element 10 from coming in contact with and damaging projections on the surface being 20 finished. Secondly, the shield protects the rotary element 10 from being damaged by projections on the working surface, which is especially necessary in the present apparatus due to the relatively high speed to which it is employed. 25 Thirdly, the shield prevents liquid and abrading material being thrown off radially due to the centrifugal action of the high speed abrading element.

As was pointed out above, the abrading element 10 has a rearwardly curved forward working surface 17. This curving surface 17 extends back into the confines of the shield 30. The result of this is that as liquid and abrading material are thrown outwardly by centrifugal action, they follow the curvature 17 for a certain distance and the major portion thereof is therefore thrown off within the confines of the shield 30. The particular cooperation between the specific form of abrading element and the shield forms 50 one aspect of the present invention.

While I have disclosed my shield element 30 as made of soft resilient material such as rubber, it should be apparent that it may be made of

other material while retaining numerous of its many advantages.

What I claim as my invention is:

1. In a device of the character described, a handle portion, a rotary body secured to said handle portion, said body having a forward face to be engaged with a surface to be finished, means for supplying liquid to the forward face of said body, a shield having a collar engaging said handle portion and supporting said shield, said shield 10 extending outwardly and forwardly from said collar in spaced relation to said rotary body and terminating in a forward edge spaced slightly rearwardly of the forward face of said rotary body, the forward face of said rotary body having 15 edges rounded to throw off liquid radially outward within the confines of said shield.

2. A device of the class described comprising a circular body having a forward working face provided with rearwardly curved outer edges, a 20 rotary driving member for said body, a housing for said driving member, means carried by the housing for supplying a liquid to the working face of the rotary body, and a cup-like shield encircling the rotary body, said shield being fixed 25 to the housing, the forward edge of the cup-like shield terminating just in rear of the forward working face of the body, and the curvature of the outer edges of the body extending well within the confines of the cup-shaped shield so that 30 the major portion of the liquid thrown outwardly by centrifugal action when the body is rotated will be within the confines of and intercepted by the shield.

3. A device of the class described comprising 35 a rotary body having a forward working face provided with rearwardly curved outer edges, a rotary driving member for said body, a housing for said driving member constituting a handle, means carried by the housing for supplying a liquid 40 to the working face of the rotary body, and a shield of resilient material encircling the rotary body and having a collar sleeved upon the housing, the forward edge of the shield terminating just in rear of the forward working face of the 45 body, and the curvature of the outer edges of the body extending well within the confines of the shield so that the major portion of the liquid thrown outwardly by centrifugal action when the body is rotated will be within the confines of and 50 intercepted by said shield.

WILLIAM R. SHIELDS.
